**COMBINED MAGNIFYING LENS AND
SUPPORT THEREFOR**

Robert W. Vernon, 11050 Moorpark,
North Hollywood, Calif

Filed Feb. 19, 1962, Ser. No. 68,883

Term of patent 14 years

(Cl. D57—1)

FIG. 1 is a perspective view of the combined magnifying lens and support therefor showing my new design; and

FIG. 2 is a side elevational view thereof on a reduced scale.

I claim:

The ornamental design for a combined magnifying lens and support therefor, as shown.
